UNITED STATES PATENT OFFICE.

JAMES HENRY JONES, OF SAN FRANCISCO, CALIFORNIA.

INJECTOR OIL-BURNER FOR BOILER-FURNACES.

SPECIFICATION forming part of Letters Patent No. 444,115, dated January 6, 1891.

Application filed July 20, 1889, Serial No. 318,118. (No model.)

To all whom it may concern:

Be it known that I, JAMES HENRY JONES, a citizen of the United States, residing at San Francisco, in the county of San Francisco and

5 State of California, have invented certain new and useful Improvements in Injector Oil-Burners for Boiler-Furnaces; and I do hereby declare the following to be a full, clear, and exact description of the invention, such as will 10 enable others skilled in the art to which it app pertains to make and use the same.

This invention relates to an improvement in devices for promoting the combustion in steam-boiler furnaces, the object being to 15 make a more complete and perfect burning of all the gases; and the invention therefore consists in the construction, arrangement, and combination of the several parts, substantially as will be hereinafter described and 20 claimed.

In the accompanying drawings, illustrating my invention, Figure 1 is a longitudinal vertical section of a marine return-flue boiler, my improved apparatus for furnishing a sup- 25 plementary fuel being shown arranged there- with and represented in dotted lines. Fig. 2 is a top plan view of the same. Fig. 3 is a left end elevation. Fig. 4 is a right end elevation. Fig. 5 is an enlarged vertical section 30 of my mechanism for injecting the concentrated fuel to be used with the common fuel.

Similar letters of reference designate corresponding parts throughout all the different figures of the drawings.

35 A denotes, in general, a marine return-flue boiler. I have selected this kind of a boiler for illustration only, and do not desire to be confined thereto, as my invention is applicable to all kinds of boilers. The boiler A has 40 the furnace B, the flues *a a* leading from the furnace B to the back connection C, and the return-flues *b b* leading from the back connection C to the uptake or chimney D. This construction of course is no part of my in- 45 vention, and is given for explanation merely.

The devices whereby I furnish the common fuel usually employed with the concentrated supplementary fuel for the purpose of promoting the combustion and insuring a more 50 complete ignition of the gases may be connected to the boiler at its furnace B or at its back connection C or at both points. In the

drawings I have shown mechanism located at both points. In Fig. 1 it will be seen connected with the furnace-chamber immediately 55 behind the grates, and also at the back connection C, where it can discharge transversely across the back connection, so as to break up and redistribute the gases at that point, as well as to completely consume them. 60

My improved device embraces the forcing of air, steam, and petroleum or other oils into the furnaces of boilers and into the rear connections, thus creating a flame which the escaping atoms of carbon will have to pass 65 through. This insures almost perfect combustion without smoke. The proper quantity of air and steam and oil will be regulated by an arrangement of valves, &c., as will be now described. 70

In order to provide a constant current of air to admit to the boiler, I use a suitable engine located, preferably, at one side of the boiler near the grate and arranged to operate a fan and thus generate a current of air. Any 75 kind of engine may be used. E denotes this engine, and *e* a horizontal air-pipe which receives the air from the fan. The engine E is driven by steam supplied through the pipe *c*. This pipe runs longitudinally alongside 80 of the boiler. It is provided with two valves *c' c'*, located on each side of the point where the vertical steam-pipe *d*, that conveys steam from the boiler, connects with the horizontal pipe *c*. (See Figs. 1 and 3.) The pipe *d* is pro- 85 vided with a valve *d'* to regulate the admission thereto of steam from the boiler and with a valve *d'*, located at its intersection with pipe *c*, so as to regulate the course of the steam, and also with valves *f* opposite the injector and valve *f'* below the latter. Mani- 90 festly steam coming through pipe *d* from the boiler will be delivered to pipe *c* and conducted thereby in two directions, under the control, of course, of valves *c' c'*, to the engine 95 E, and to the injecting devices adjacent to the back connection C. The pipe *d* also de- 100 liver steam to the injector which admits air, steam, and oil to the furnace B. The pipe *e* carries air into the upper end of the inject- ing device. The pipe *g* carries oil up from the oil-reservoir F into the injector.

In Fig. 5 I have shown in an enlarged sec- tional view the detailed construction of the

injector which throws the oil, air, and steam into the furnace or into the back connection, as the case may be. By referring to that figure it will be seen that steam coming through 5 steam-pipe *d* enters the horizontal tube *G*. The oil is conveyed into the injector by the pipe *g*, which is differently arranged from what is shown in Figs. 1 and 3. The pipe *g* delivers the oil into the vertical pipe *h*, located 10 within the cylindrical barrel *H*, which is entered by the air-pipe *e*, as shown. The lower end of pipe *h* opens into a tube *I*, which surrounds the tube *G*, it being so arranged as to afford an annular space between itself and 15 said tube *G*, the ends of which space are closed, but the pipe *I* communicates with pipe *G* through openings or small apertures in the wall of the latter, as shown at *i i*, so that oil coming through pipe *h* will mingle with the 20 steam within the tube or pipe *G*. The end of tube *G* is formed with an opening *J*, within which is located a tapering plug *K* on the end of a rod *k*, extending through the tube *G*, its other end being screw-threaded and located 25 in a screw-threaded box and provided with an external hand-wheel by the manipulation of which the plug *K* can be adjusted so as to open or close the mouth or nozzle *J*. Through the nozzle *J* the commingled steam and oil 30 will be ejected by reason of the pressure in the pipes which convey these substances into the injector. Air enters the device through pipe *e* and fills the annular space around the pipe *h* within the cylinder *H*, through which 35 it passes downward into the cylinder *L* and into the annular space around the aforesaid tube *I*, said cylinder *L* being open-ended, so as to provide the mouth *M*, through which the air is discharged, this discharge of the air being 40 effected and facilitated by the induction action of the current of commingled steam and oil passing out through the opening *J*. Thus it will be manifest that the air, steam, and oil will be injected at any point where the 45 mouth *M* may be located, and hence if it be placed within the furnace it will be apparent that the injector will add to the common fuel in said furnace the concentrated fuel consisting of air, oil, and steam, and thus the 50 combustion will be promoted in accordance with the principles already hereinabove described.

I have now described the injector which 55 delivers the concentrated fuel into the furnace and have explained the operation and purpose of the same. Another injector is usu-

ally and preferably located so as to deliver concentrated fuel into the back connections of the boiler; but as the construction of both injectors is substantially the same it is needless to repeat the description of the construction and use of the latter.

Having thus described my invention, what I claim as new, and desire to secure by Letters Patent, is—

1. The combination of the boiler *A*, the engine *E*, arranged to generate a current of air, the air-fan operated by said engine, the horizontal air-pipe *e*, which receives air from the fan, the steam-pipe *c*, for supplying steam to 70 drive the engine *E*, said steam-pipe *c* being provided with valves *c' c'*, located on each side of the point where the vertical steam-pipe *d* connects with the horizontal pipe *c*, the vertical steam-pipe *d*, that conveys steam 75 from the boiler, said pipe having a valve *d'* to regulate the admission thereto of steam from the boiler, and also with a valve *d'*, located at its intersection with pipe *c*, so as to regulate the course of the steam, and also with 80 a valve *f* opposite the injector and a valve *f'* below the latter, and the injector-tube *G*, with valve *K* located in the end of said tube, substantially as described.

2. The combination of the boiler *A*, the engine *E*, arranged to operate a fan and thus generate a current of air, the injector consisting of tube *G*, having mouth *J*, the valve *K*, located within said mouth, said tube *G* having also the openings *i i*, the oil-tube *I*, 90 surrounding the tube *G*, the air-tube *L*, the air-fan, the horizontal air-pipe *e*, which receives the air from the fan, the steam-pipe *c*, for supplying steam to drive the engine *E*, said steam-pipe *c* having valves *c' c'* located 95 on each side of the point where the vertical steam-pipe *d* connects with the horizontal pipe *c*, the vertical steam-pipe *d*, for conveying steam from the boiler, said pipe *d* having a valve *d'* to regulate the admission thereto 100 of steam from the boiler, and with a valve *d'*, located at its intersection with pipe *c* to regulate the course of the steam, and also with the valve *f* opposite the injector and the valve *f'* below the latter, substantially as 105 described.

In testimony whereof I affix my signature in presence of two witnesses.

JAMES HENRY JONES.
